UNITED STATES PATENT OFFICE.

ARTHUR HENRY LYNN, OF WESTMINSTER, LONDON, AND NIELS EDWARD RAMBUSH,
OF STOCKTON-ON-TEES, ENGLAND.

GAS PRODUCER.

Application filed April 24, 1919, Serial No. 292,428, and in Great Britain May 17, 1918.

The present invention relates to improvements in and relating to gas producers.

In connection with the working of gas producers it is well known that in order to obtain the most economical results and the best gasifying effects that the gaps formed in the mass of the fuel due to caking, should be caused to fill up and clinkering of the ash should be prevented.

10 For this purpose it is the practice to moderately agitate the charge by mechanically raising and lowering the whole or part of the revolving base in relation to the stationary part of the producer.

15 Generally the means used consisted in the arrangement of a conical grate with spiral steps thereupon, or by providing helical convolutions cut away to form faces adapted to break up the clinker and convey the same towards the pan, which helical surfaces, 20 may, in some cases gradually merge into cylindrical contour.

In such known devices a great number of spaces are left between the projecting and cut-away portions of the surface which quickly fill up with hard setting clinker and ashes, so that the device is bound to act, after a short time, more or less as a cone, thus failing not only to raise and lower the fuel but also to convey the ashes towards the shell of the producer.

25 In other known devices only a few raising surfaces are provided on the revolving grate, so arranged that they terminate very abruptly so as to provide a steep and abrupt drop for the fuel, thus enabling the clinkers to be broken up and to fall into radially arranged channels or into a horizontal grate provided with openings for the blast.

30 For such devices generally, one driving mechanism is used to revolve the grate, and another driving mechanism is required for driving the ash removal devices.

35 Moreover the blast holes in such known devices fill up rapidly with clinker and impair the smooth working of the producer.

In order to obviate these disadvantages in one construction used in practice, a grate has been fixed on a revolvable ash-bowl and the upper side of said grate has been provided with spiral configurations having a very gradual rise terminated by abrupt shoulders of considerable depth, in which the openings for the blast are arranged in

such way that the fuel and ashes cannot 55 obstruct said holes.

It has been found with certain classes of fuel, that abrupt shoulders of considerable depth cause the charge to drop too abruptly and suddenly, which with certain kinds of 60 fuel, may lead to irregular working of the producer.

The present invention aims at obviating this disadvantage and at providing a revolvable grate adapted to work with any 65 kind of fuel.

According to the invention we provide means by which whilst a considerable total drop of the charge is retained, the drop of the charge is rendered less sudden and 70 abrupt.

The invention also provides for constructional improvements, with the object of reducing the cost of manufacture.

75 In order to understand the invention more clearly reference is made to the accompanying drawing which shows by way of example one construction.

The following description is to be read in the light of direction of rotation of the 80 ash bowl as indicated by the arrow.

Fig. 1 shows an elevation partly in section of the lower part of the gas producer with the revolvable grate.

Fig. 2 is a sectional plan on the line x—x 85 of Fig. 1.

Fig. 3 is a vertical section through the grate of a modification, showing the interconnection of the bars of the grate, and

Fig. 4 is an elevation looking along the 90 arrow shown in Fig. 3.

Referring to the drawings, a indicates the ash bowl, b is the producer shell or casing, c the inner lining of the producer, d a cylindrical shell forming the extension of the 95 producer shell into the ash bowl, and g is the grate or blast distributor, fixed to the revolvable ash bowl a by bolts and nuts u.

The ash bowl a is adapted to revolve on rollers f. The rotation is effected by providing a toothed ring z around the periphery of said ash bowl. Engaging said toothed ring is a spur wheel s, driven by a shaft t.

100 As will be seen from Fig. 2 the grate g is constructed in four parts, each part consisting of two sections. One section serves to gradually raise the charge and the other section serves to drop it again.

The surface of each raising section h, i, l, k , has a gradual upward slope the point h of each of said raising sections being lower than the point i , whilst the point k of each of said raising sections is lower than the point l . The gradual slope of the surface between the points h, k, l, i of each of said raising sections is preferably slightly curved.

In each raising section the boundary line i, l , indicates its highest surface level, and the boundary line h, k , of each raising section indicates its lowest level. The differences in level between the said boundary lines i, l , and h, k , represent the total rise of the producer charge.

The drop sections according to the present invention are made less abrupt and sudden than in known constructions by providing between the highest level i, l , of each raising section and the lowest level h, k , of each next raising section a series of horizontal steps m , suitably supported at m' and spaced apart by bridge pieces q leaving intermediate gaps r so as to form a sloping step grate, of gradual average slope, and the blast which enters from below the grate through the luted inlet pipe n issues through said gaps r between the steps m , while an additional outlet may be provided around the part p covering the blast inlet.

The steps m are preferably made in such way that they interlock with each other, and so that they can be easily replaced.

As will be seen from Fig. 3 only one bar m is fixed to the grate g by means of a bolt and nut v the remaining bars mutually keeping each other in position by means of the aforesaid bridge pieces q .

We claim:

1. In a gas producer, a stationary shell, a revoluble ash bowl and a grate fixed upon said ash bowl, the upper side of said grate being formed of a plurality of wave-like sectors radiating from a common point situated within the periphery of said grate, said wave-like sectors being relatively wide in the horizontal direction, gradually rising to a peak and thereupon sloping gradually downwardly, thereby providing only a few upwardly directed projections.

2. In a gas producer, a stationary shell, a revoluble ash bowl and a grate fixed upon said ash bowl, said grate having the shape of laterally displaced vertical sections of a cylinder and having a series of wave-like upper surfaces radiating from a common point situated within the periphery of said grate, said wave-like surfaces being relatively wide in the horizontal direction and gradually rising to a peak and thereupon sloping gradually downwardly, thereby

providing only a few upwardly directed projections.

3. In a gas producer, a stationary shell, a revoluble ash bowl and a grate fixed upon said ash bowl, the upper side of said grate being formed of a plurality of wave-like sectors radiating from the axis of rotation of said grate said wave-like sectors being relatively wide in the horizontal direction and gradually rising to a peak and thereupon sloping gradually downwardly, thereby providing only a few upwardly directed projections.

4. In a gas producer, a stationary shell, a revoluble ash bowl and a grate fixed upon said ash bowl, the upper side of said grate being formed of a plurality of wave-like sectors radiating from a common point situated within the periphery of said grate, said wave-like sectors being relatively wide in the horizontal direction and gradually rising to a peak and thereupon sloping gradually downwardly, thereby providing only a few upwardly directed projections, said downwardly sloping surfaces being built up of bars separated by gaps.

5. In a gas producer, a stationary shell, a revoluble ash bowl and a grate fixed upon said ash bowl, the upper side of said grate being formed of a plurality of wave-like sectors radiating from a common point situated within the periphery of said grate, said wave-like sectors being relatively wide in the horizontal direction and gradually rising to a peak and thereupon sloping gradually downwardly, thereby providing only a few upwardly directed projections, said downwardly sloping surfaces being provided with blast orifices.

6. In a gas producer, a stationary shell, a revoluble ash bowl, a grate fixed upon said ash bowl, said grate consisting of vertical semi-cylinders eccentrically arranged relatively to each other and to the axis of rotation of the grate in such a way that their cylindrical surfaces at the ends remote from said axis of rotation protrude laterally towards said shell, the upper side of said grate being formed of a plurality of wave-like sectors radiating from a common point situated within the periphery of said grate, said wave-like sectors being relatively wide in the horizontal direction, gradually rising to a peak and thereupon sloping gradually downwardly, thereby providing only a few upwardly directed projections.

In testimony whereof, we affix our signatures.

ARTHUR HENRY LYMN.
NIELS EDWARD RAMBUSH.
